UNITED STATES PATENT OFFICE.

GEORGE ANDREJCAK AND MICHAEL SALONY, OF LILLY, PENNSYLVANIA.

HAND-GRENADE.

1,151,433.

Specification of Letters Patent. Patented Aug. 24, 1915.

Application filed June 10, 1915. Serial No. 33,287.

To all whom it may concern:

Be it known that we, (1) GEORGE ANDREJCAK and (2) MICHAEL SALONY, (1) subject of the King of Hungary and (2) a citizen of the United States, residing at Lilly, in the county of Cambria and State of Pennsylvania, have invented certain new and useful Improvements in Hand-Grenades, of which the following is a specification.

10 This invention relates to certain new and useful improvements in hand grenades.

The primary object of the invention is to provide an explosive bomb adapted for hurling at the enemy after igniting a fuse 15 for the purpose of killing large numbers of persons by means of soldiers without the aid of machines or guns.

A further object of the invention is to provide a container for death dealing elements, the same being provided with a hand means for throwing the same and being adapted to explode when dropped among the enemy.

A still further object of the device is to provide a hand throwing container being arranged for the central reception of a fuse ignited explosive and surrounded by bullets adapted to be scattered by the explosive.

With these general objects in view and others that will appear as the nature of the invention is better understood, the same consists in the novel combination and arrangement of parts hereinafter more fully described, illustrated in the accompanying drawings and pointed out in the appended claim.

In the drawings forming a part of this application and in which like-designating characters refer to corresponding parts throughout the several views, Figure 1 is a central longitudinal sectional view of the device, and Fig. 2 is a top plan view thereof, in its normal position.

Referring more in detail to the drawings, 45 a container 10 is provided preferably formed of metal and being substantially vase or pear shaped and provided with an inlet 11 in the neck 12 thereof.

A sack or bag 13 contains an explosive 14 such as powder, in a somewhat loose form and has a tube 15 radially projecting therefrom and provided with an ignition fuse 16 extending therethrough and projecting beyond both ends thereof. The sack is adapt-

ed to be forced through the inlet of the receptacle so as to be suspended substantially centrally therein and then allows the bullets 17 or other missiles which are desired to be projected at the enemy to be inserted through the said inlet 11 and position themselves circumferentially of the said sack and so as to fill the receptacle substantially to the threaded annular shoulder 18 within the neck 12 and as best illustrated in Fig. 1. A closure disk 19 is provided with a central perforation 20 for closely fitting the tube 15 when slidably mounted thereon and is positioned in screw-threaded engagement with the afore-mentioned shoulder 18 for closing the receptacle. A desired form of sealing composition such as wax 21 is arranged within the outer end of the inlet 11 thus leaving the tube 15 as the only means of access to the explosive 14.

Oppositely arranged staples 22 are positioned upon the receptacle neck and are provided with a flexible bail 23 connecting the same and by means of which the grenade may be readily carried and also thrown short distances. A throwing handle 24 is arranged having a hook 25 at one end thereof adapted to be inserted in either of the said staples and has a hand loop 26 at its opposite free end.

From this detailed description of the entire device, it will be seen that after the grenade has been formed in the manner set forth, the same is ready for use in times of war and may be employed by soldiers against their enemy. The fuse 16 is first lighted at the outer end thereof and the handle 24 positioned in place by grasping the hand loop 26, the grenade may be swung in an arcuate or circular path and upon being released will fly for a considerable distance into the midst of the enemy and as soon as the fuse is burned inwardly and ignites the explosive 14, the latter will explode exerting its force upon the bullets 17 and projecting the same in all directions. It will be thus seen that an efficient grenade is arranged which may be readily carried by the soldiers and employed for use whenever desired.

While the form of the invention herein shown and described is what is believed to be the preferred embodiment thereof, it is nevertheless to be understood that minor

changes may be made without departing from the spirit and scope of the invention as claimed.

What we claim as new is:—

- 5 A hand grenade comprising a vase-shaped receptacle having an inlet in the neck thereof, an explosive containing sack insertible through the said inlet to a central position within the said receptacle, a tube radially 20
10 projecting from the said sack, an ignition fuse extending through the said tube and projecting outwardly at both ends thereof, a closure disk slidably mounted upon the said tube, and screw-threaded within the 15 said neck, a sealing composition closing the

outer end of the said inlet and in contact with the said tube and disk, staples oppositely positioned upon the outer edge of the receptacle neck, a flexible bail connecting the said staples, and a hand-engaging handle removably arranged in hooking engagement with one of the said staples.

In testimony whereof we affix our signatures in presence of two witnesses.

GEORGE ANDREJCAK.
MICHAEL SALONY.
